CLAIM

The ornamental design for a planer bit, as shown and described.

DESCRIPTION

FIG. 1 is a side elevational view of the planer bit design of the present invention, the reverse side of which is a mirror image thereof.

FIG. 2 is a top plan view of the planer bit of FIG. 1.

FIG. 3 is a view of one end of the planer bit of FIG. 1.

FIG. 4 is a bottom view of the planer bit of FIG. 1.
FIG. 5 is a view of the planer bit of FIG. 1 taken at the other end of that shown in FIG. 3.
